DAM CONSTRUCTION

Arthur O. Neuman, San Antonio, Tex.

Application May 2, 1938, Serial No. 205,549

2 Claims. (Cl. 61—30)

This invention relates to concrete dam construction, and more particularly to the construction of drain tiles used in the construction of dams.

5 An important object of the invention is to provide a concrete drain tile constructed in such a way that when properly positioned during the construction of a dam, will convey all moisture and surplus water from the wet concrete mass of 10 which the body of the dam is constructed, to facilitate rapid and exact curing of the concrete mass.

15 Another important object of the invention is to provide drain tiles forming a permanent part of the dam construction, and having such a degree of porosity that air may be forced through the drain tile to facilitate and promote the rapid and accurate curing of the mass concrete in which the tiles are embedded.

20 A still further object of the invention is the provision of a drain tile of such strength and durability that it may become a permanent element in the dam construction to carry off moisture that otherwise is forced through the concrete under the intense hydraulic pressure, set up behind the dam when in use, and which eventually results in undermining the foundation of the dam.

25 With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

30 Referring to the drawings:

35 Figure 1 is a vertical sectional view through a dam constructed in accordance with invention, and illustrating tiles, forming the subject matter of the invention, as positioned in the concrete mass or body portion of the dam.

40 Figure 2 is an enlarged fragmental sectional view illustrating the lowermost tile of a tier of tiles, illustrating the connection between the tiles and laterally extended drain tiles that connect with the main drain pipe of the dam.

45 Figure 3 is a fragmental elevational view illustrating the manner of building up tiers with the tiles, as well as the means for anchoring the tiers in position.

50 Figure 4 is a longitudinal sectional view through connected tiles, and illustrating the variation

in porosity of the ends of the tile and central portions thereof.

Figure 5 is an end elevational view of one of the tiles.

5 Referring to the drawings in detail, tile sections constructed in accordance with the invention, are indicated generally by the reference character 5, and as shown, each tile section includes a central portion 6 of such porosity that water will pass therethrough at the rate of seven 10 gallons per minute, with a constant four inch depth of water in the slab at the bottom thereof.

15 In constructing the central or body portion of each tile section, the proportions of materials used are approximately one part of cement to five parts of pea gravel by weight, and a water cement ratio of 0.33 by weight, or of a consistency so that the paste formed will not fill the voids in the aggregate, but will thoroughly coat and bind the aggregate particles. The aggregate is carefully prepared, and only an aggregate is used 20 which is of a size to pass a screen having $\frac{3}{8}$ -inch square or equivalent round openings, and which will be retained in a screen having $\frac{1}{16}$ -inch square or equivalent round openings.

25 The ends of each tile section, and which provide the joints between adjacent sections, embody a mixture of cement mortar mixed in the proportion of 1 part of Portland cement to $1\frac{1}{2}$ to 2 parts, by weight, of sand. After the materials have been mixed in the proportions specified, the materials are placed in suitable molds and vibrated until sufficiently packed. After a predetermined time, the molds are removed and each finished tile is covered carefully with burlap and cured for fourteen days. Intermittently, water is applied to the burlap covered tiles, to facilitate proper curing of the concrete.

30 In the use of the tiles with a dam construction, the tiles are arranged one above the other in the formation of vertical tiers, indicated by the reference character 9 in Figure 1 of the drawings. In positioning the tiles, the reduced tapered end 7 is positioned within the recessed end 8 of the adjacent lower tile section. The lowermost tile section of each tier is positioned in the elbow 10 of the pipe 11 associated therewith, the pipe 11 communicating with the usual drainage gallery 13 of a dam construction, 45 where the moisture or water will be carried off.

40 In the construction of the dam, the pipe sections are positioned, and the concrete mass is placed around the tile sections, and as the concrete is built up, additional tile sections are 50 55

added, until the concrete has reached the desired height of the dam.

When the last sections of the tiers have been positioned, caps 14 are positioned over the upper ends of the uppermost sections. Guy-wires 15 are connected to opposite sides of the caps 14, the opposite ends of the guy-wires 15 being anchored in the concrete mass forming the dam, as by means of the U-bolts 16. Thus it will be seen that due to this construction, the tiers of pipe sections are firmly secured and held in upright positions at all times.

It might be further stated that the usual operating gallery 18 may also be drained through these tiles, which are in communication with the operating gallery, through the pipes 17. Due to the construction shown and described, it will be obvious that a dam supplied with drain tiles constructed in accordance with the invention, will drain readily, insuring a rapid and exact curing of the concrete mass.

I claim:

1. A dam construction comprising a body portion formed of a mass of plastic material, a plurality of tiers of drain tile arranged in transverse spaced relation with respect to each other, embedded within the plastic material, drainage galleries formed in the body portion, pipes establishing communication between the drain tiles and galleries, and said drain tiles being constructed of plastic material whereby moisture may find its way into the drain tiles through the walls thereof.

2. A dam construction comprising a body portion formed of a mass of plastic material, a plurality of tiers of vertical drain tiles arranged in transverse spaced relation with respect to each other and embedded within the body portion, each of said drain tiles embodying a porous central portion and non-porous ends, the lower end of one tile being fitted in the upper end of the adjacent lower tile section, and horizontal pipes communicating with the vertical drain tiles and embedded in the body portion near the base thereof, whereby moisture drains through the walls of the drain tiles and passes downwardly into the horizontal pipes.

ARTHUR O. NEUMAN.
